DESIGN FOR A RECORD CABINET

Henry E. Braloff, Rockville Centre, N. Y.

Application February 17, 1944, Serial No. 112,607

Term of patent 7 years

(Cl. D33—10)

To all whom it may concern:

Be it known that I, Henry E. Braloff, a citizen of the United States and a resident of Rockville Centre, in the county of Nassau, State of New York, have invented a new, original, and ornamental Design for a Record Cabinet, of which the following is a specification, reference being had to the accompanying drawing, forming part thereof, in which:

Figure 1 is a perspective view of a record cabinet, showing my design as it appears when in opened position; and

I claim:

The ornamental design for a record cabinet, as shown and described.

HENRY E. BRALOFF.
